(57) **CLAIM**

The ornamental design for a case for electronic device as shown and described.

DESCRIPTION

FIG. 1 is a front, left and top perspective view of a case for electronic device in accordance with the first embodiment of our design;

FIG. 2 is a rear, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is another front perspective view thereof, showing a stand of the case for electronic device in an open position;

FIG. 10 is another front perspective view thereof, showing the stand of the case for electronic device in another open position;

FIG. 11 is a front, left and top perspective view of a case for electronic device in accordance with the second embodiment of our design;

FIG. 12 is a rear, right and top perspective view thereof;

FIG. 13 is a front view thereof;

FIG. 14 is a rear view thereof;

FIG. 15 is a left side view thereof;

FIG. 16 is a right side view thereof;

FIG. 17 is a top view thereof;

FIG. 18 is a bottom view thereof;

FIG. 19 is another front perspective view thereof, showing a stand of the case for electronic device in an open position;

FIG. 20 is another front perspective view thereof, showing the stand of the case for electronic device in another open position;

(Continued)

FIG. 21 is a front, left and top perspective view of a case for electronic device in accordance with the third embodiment of our design;
 FIG. 22 is a rear, right and top perspective view thereof;
 FIG. 23 is a front view thereof;
 FIG. 24 is a rear view thereof;
 FIG. 25 is a left side view thereof;
 FIG. 26 is a right side view thereof;
 FIG. 27 is a top view thereof;
 FIG. 28 is a bottom view thereof;
 FIG. 29 is another front perspective view thereof, showing a stand of the case for electronic device in an open position; and,
 FIG. 30 is another front perspective view thereof, showing the stand of the case for electronic device in another open position.
